UNITED STATES PATENT OFFICE.

JOHN J. SNYDER, JR., OF FLATBUSH, NEW YORK.

FERTILIZER-DISTRIBUTER.

SPECIFICATION forming part of Letters Patent No. 352,158, dated November 9, 1886.

Application filed March 2, 1886. Serial No. 193,709. (No model.)

To all whom it may concern:

Be it known that I, JOHN J. SNYDER, Jr., a citizen of the United States, residing at Flat-bush, in the county of Kings and State of New York, have invented new and useful Improvements in Fertilizer-Distributors, of which the following is a specification.

My invention relates to that class of fertilizer-distributors which distribute the fertilizing material in the drill.

The objects of my invention are simplicity and durability in the construction of the implement, constant and even dropping of the fertilizing material, and the thorough mixing the same with the soil. I attain these objects by the mechanism hereinafter described, and illustrated in the accompanying drawings.

Figure 1 is a side elevation of the implement, cut longitudinally through the center, the right-hand side being removed and the traveling wheel and its shaft, the hopper, hopper-slide, brace, slide-spring, and cross parts of the frame being in section and the driving pulleys being in dotted lines. Fig. 2 is a detail or side view of the roller and its distributing arched pins or teeth.

Similar letters of reference refer to like parts in the views.

The frame is in general construction similar to that of a wheel-barrow. A is the handle; A', its leg. a a' are cross bars or timbers, which extend across from one handle to the other. a a' are also cross-bars, which assist in forming a seat for the hopper.

B is the traveling wheel, fast on the shaft B', which has its journals in journal-bearings on the front ends of the handle or main timbers of the frame.

B' is a wheel fast on the outer end of shaft B' at the left-hand side of the implement.

C is a hopper, which is placed back of the wheel B. It is supported and held in position by the handle timbers A and the cross-bars a a'. Its sides are inclined in the usual way, but terminate at the bottom in a square box-formed projection, as shown by C'. The back of this box c is cut off at its top, so as to leave a slot or opening between it and the bottom edge of the inclined back of the hopper.

Through this opening the slide-valve E enters the hopper, as hereinafter described.

C' is an octangular roller, which is located

at the bottom of the hopper, just above the slide-valve. It is fast on the shaft c', which extends through the sides of the hopper and journals in bearings on the timber A.

C' is a wheel which is fast on the roller shaft c' and in line with the driving-wheel B'. These wheels B' and C' have pins projecting from their faces at regular intervals, thus forming them into sprocket-wheels. A flat chain, having its links in correspondence to the pins on the periphery of said wheels, conveys motion from the wheel B' to the wheel C', and thus causes the roller to revolve in the hopper. This way of driving the roller I find to be much superior to any other, as the roller is forced to revolve as the implement moves forward, and by its action the fertilizer is forced out at the valve-opening of the hopper; nor can the roller be stopped by the clogging of it by the fertilizer, as is the case where an ordinary belt and pulleys are used.

D is a flat iron brace. Its top is bolted to the outside of the hopper-back. From thence it extends down until on a line with the lower edge or mouth of the box c, and curves slightly toward the front in its course. It then is bent to about a right angle a few inches back of the box c, and then extends to and is attached to the lower edge of the back of said box, which it braces. In its downward course it is perforated by a hole, d, which is in line with the opening in the back of the box C'. It has also a slot, d', in its horizontal portion between its point of bend and its connection with box C'.

E is a slide or cut-off valve, as shown in Fig. 1. It is of such size as will close the bottom of the hopper, and moves longitudinally therein through the opening in the box back. It is provided with suitable guides in the box-sides. From its back edge extends its rod E', which is of such length that it will, (when the valve is closed,) extend through the hole d in the brace D and terminate just back of said brace. At this, its free end, it is provided with a hole, into which is hooked a short adjusting-rod, F, which in turn is provided at its rear end with a vertical longitudinal slot about three inches in length.

F' is a long rod, having a handle, f, on its upper or rear end. It extends through an iron loop, f', by which it is supported, (said loop

being attached by its upper ends to the center of cross-bar a ,) and just in front of said loop it is provided on its under side with a notch, f^3 , which corresponds to the size of the arch 5 of the loop f^2 , so that it can be hooked on it. This rod is terminated at its front end by having its end turned down at a right angle, so as to pass through the slot in the adjusting-rod F . This portion is about two or three 10 inches in length, and is screw-threaded and provided with a thumb-nut, f^4 , by which the connection of the rod F' can be clamped to various points in the slot in rod F .

The roller c^2 is provided with a series of 15 arched pins or staples, C^3 , which project from alternate sides. Thus this roller or agitator being octagonal in form, it will be seen has only four of its sides occupied by its staples, and that these staples are arranged so that 20 those of one row do not immediately follow those of the next preceding one, as is clearly shown in Fig. 2. The operation of this arrangement is that the octangular sides of the roller act to move or displace the fertilizing 25 material and prevent it from packing, as it would do if the roller were cylindrical. At the same time the teeth, being arched, act on the material, not only in a longitudinal direction, but also in a lateral, and act to disintegrate 30 any lumps that may have formed in the material.

G is the left-hand side of a frame, of which G^2 is the cross-bar, from which project the covering-teeth g^2 . This frame is hung on pivots 35 g^2 , to and between the legs A' . Its teeth consist of one cultivator-tooth with an ordinary harrow-tooth at each side and a little to the rear of it. By the use of a cultivator-tooth in addition to the use of harrow-teeth I find that the fertilizing material is more thoroughly mixed with 40 the soil. In the drawings the harrow is shown as raised out of operation. It is held in this position by the button H , (see Fig. 1,) which consists of a strap of iron pivoted to the timber 45 A just above the leg A' . It is several inches in length, and at its lower end is bent on itself, so as to bear on the upper end, front, and inner side of the harrow-frame G . When it is desired to place the harrow in operation, this button is 50 slipped up and over the end of the piece G , and so allows the harrow to drop or turn down on

its pivots, its cross-bar G^2 bearing against the leg cross-bar a' , thus holding the teeth to their work. The arrangement and construction of the rods F and F' are such that the opening 55 in the bottom of the hopper can be adjusted to any necessary size by the changing of the connection of the rod F' with the rod F , by means of the thumb-nut f^4 , so as to make the connecting-point higher or lower in the slot. 60

I is a spring which is attached to the back of the hopper C , and extends down through the valve or slide rod E^2 and the horizontal slot in the brace D . Its action is to close the valve-opening in the bottom of the hopper. 65

When it is desired to operate with the machine, the opening of the valve is first arranged as desired by the adjustment of the connection of the rods F F' , the harrow is released from the button H , and the implement is moved 70 forward. The roller revolves in the hopper, causing the fertilizing material to drop through the valve-opening, which is held open by the notch of the rod F being hooked on the horizontal part of the loop f^2 . 75

It will be understood that a horse may be attached to the implement by any well-known device.

I do not wish to be understood as confining myself to the octangular form of the roller or agitator, as a square form might be substituted, or even a septangular or other forms, in which case, however, the teeth should be placed at the angles, and any of them will be found superior to the usual cylindrical form; yet I believe the octangular to be the best. 85

I claim—
1. In a fertilizer-distributer, the combination of the hopper C , box C' , slide-valve E , having the rod E^2 , the spring I , and brace D , 90 as and for the purpose described.

2. In a fertilizer-distributer, the combination of the adjusting-rod F , provided with a longitudinal slot, e , in its upper end and connected to the slide-valve E , and the rod F' , 95 having a screw-threaded end adjustable in said slot, and a nut, all as described, for the purpose of gaging the valve-opening.
